UNITED STATES PATENT OFFICE.

CHARLES L. LAWRENCE, OF BAY SHORE, LONG ISLAND, NEW YORK, ASSIGNOR TO
LAWRENCE AERO ENGINE CORPORATION, A CORPORATION OF NEW YORK.

BIG END CONSTRUCTION FOR MOTORS.

1,404,617.

Specification of Letters Patent. Patented Jan. 24, 1922.

Application filed May 7, 1920. Serial No. 379,583.

To all whom it may concern:

Be it known that I, CHARLES L. LAWRENCE, a citizen of the United States, residing at Bay Shore, Long Island, county of 5 Suffolk, State of New York, have invented certain new and useful Improvements in Big End Constructions for Motors, of which the following is a specification.

The subject matter involved in the present case is a big end construction for motors and particularly those motors of a radial type in which a plurality of connecting rods are assembled on a single crank pin. In 10 motors of this type a popular form of construction is one in which a bearing foot is provided on the end of each connecting rod, these feet being guided in an annular way on a bearing encircling the crank pin. Such structures have many points of advantage 15 but have developed certain difficulties among which may be noted those resulting from the tendency of the foot to skew the race-way.

It is therefore the object of the present invention to so improve the interrelated parts 20 of such a big end construction as to afford a maximum bearing surface for the foot and at the same time to provide preventative means for the avoidance of any skewing 25 tendency of the rod foot.

As illustrative of the present invention there is shown a big end construction in detailed design as being one which has been found well adapted for practical use. The 30 specific design is not however to be construed as indicating any limitation of the invention to detail, but as being illustrative and explanatory of the invention itself. Throughout the specification and drawings 35 like reference characters are correspondingly employed, and in the drawings:

Fig. I is a vertical section through the big end assembly.

Fig. II an elevation of the same.

Fig. III an end view of a connecting rod.

Fig. IV a side view of the same.

Fig. V an end view of the rod showing the foot, and

Fig. VI a section on the line VI—VI of 50 Fig. V.

In the construction shown, there is provided on the crank pin 1 a pair of ball bearings 2 assembled within the ring 3 which acts as a guideway for the feet of a

plurality of connecting rods 4. The foot of 55 each of the connecting rods as will be more clearly seen by reference to Figs. III, IV and V consists of a slightly arched diagonally disposed segment 5 on the end of the connecting rod. This portion 5 constitutes 60 the foot proper but is provided on each side with lateral flanges 6. It will be understood that where a large number of cylinders are used the rod foot must be relatively small. It is of the utmost importance 65 however that the arc of bearing of the foot be as large as possible. For this reason I form each rod foot at an angle to the axis of the bearing. This gives a maximum arc and also staggers the flanges 6 and decreases 70 the tendency to skew. By reference to Fig. V therefore it will be seen that the foot 5 is cut at each end on a diagonal or oblique line instead of straight across or at right angles. The two ends of the foot are cut 75 on the same angle so that the foot forms in plan a parallelogram flanged as at 6 on each narrow side which brings the flanges at different circumferential portions.

The flanged foot thus described has its 80 main or direct bearing on a sleeve or bearing 8 which is assembled within the two parts 85 9 and 10 of the guideway. In the structure shown, this guideway is divided in a plane which permits the ready assembly, the two parts being fastened by the screws 11 passing through the flanges 12 and 13, formed 90 within the ring. The width of the bearing 8 just referred to is somewhat less than the 95 internal breadth of the ring so that on each side of the bearing 8 between it and the inner side walls of the ring members 9 and 10 there is left a narrow groove or channel. In this channel the flanges 6 are guided. By 100 reason of the shape of the foot 5 these flanges have a somewhat staggered relation which gives a greater distribution of any strain resulting from tendencies of the connecting rod to twist. In some cases it has been found 105 advisable to slightly modify the shape of the foot 5 locating it more or less unsymmetrically with reference to the connecting rod, but it will be understood that any such modification in the distribution of flanges are within the spirit of the invention.

In combination with the bearing shown, the crank pin 1 preferably has an integral

part with an arm 14 on one portion of the shaft 15. The other crank arm 16 on the shaft portion 17 is preferably provided with an opening 18 which is tapered to receive the 5 tapered end 1¹ of the crank pin 1. The end of the crank pin is drawn tight in this taper by a threaded holding member 19 tapped into the open end of the pin 1 which is preferably formed hollow. The member 19 has 10 an enlarged head 19¹ to afford suitable bearing on the arm 14. In addition to the modifications possible in the shape of the foot as hereinbefore mentioned, various other modifications may obviously be resorted to in 15 other parts of the structure and combination thereof, all these are deemed to be within the purview of this invention if within the limits of the appended claims.

What I therefore claim and desire to set 20 out by Letters Patent is:

1. In a crank pin assembly, a crank pin bearing sleeve, a peripheral guideway about said sleeve and having an inward groove, a plurality of footed connecting rods assembled on said way, each rod foot having a lateral toe flange disposed in said groove and guided thereby.

2. In a big end construction of the class described, a connecting rod foot comprising 30 a central bearing portion, and a depending lateral flange on each side of said foot.

3. In a crank pin assembly a crank pin bearing sleeve, a peripheral guideway about said sleeve and having an inward groove at 35 each side thereof, a plurality of footed connecting rods assembled on said way, each

rod foot having lateral toe flanges disposed in said groove and guided thereby.

4. In a big end construction of the class described, a connecting rod foot comprising 40 an arched central bearing portion having its ends disposed at an angle to the axis of rotation, and a pair of depending lateral flanges on each side of said foot.

5. In a crank pin assembly a crank pin 45 bearing sleeve, a peripheral guideway about said sleeve and having an inward groove at each side thereof, a plurality of footed connecting rods assembled on said way, each rod foot having its ends disposed at an angle to 50 the axis of rotation, and a depending lateral flange on each side of said foot, the members of each pair being disposed at opposite ends of the foot side.

6. A connecting rod foot for a crank pin, 55 comprising a central bearing portion, and depending flanges at each end of said central portion disposed at an angle to the axis of rotation of the crank pin.

7. A connecting rod foot for a crank pin, 60 comprising an arched central bearing portion, and depending flanges at each end of said central portion disposed parallel to each other and at an angle to the axis of rotation of the crank pin.

In testimony whereof I affix my signature in presence of two witnesses.

CHARLES L. LAWRENCE.
